DISPLAY DEVICE

George de Verry, Springfield, Mass.

Application May 25, 1939, Serial No. 275,743

3 Claims. (Cl. 40—62)

This invention relates to improvements in display signs and is directed more particularly to improvements in a novel display apparatus constructed to be capable of presenting a multiplicity of different representations successively.

It is one of the principal objects of my invention to provide a display device which is adapted to attract the attention of passersby by virtue of certain novel and unique effects which it produces. As special features, it contains parts movable relative to one another arranged to permit changing of the display when desired and, in some cases, the sign is automatically changed at predetermined intervals.

Other prime objects include the provision of a display device which is relatively simple in its construction so as to be economical in its manufacture yet its construction is such that it is reliable in its operation in accordance with the demands of creative display manufacturers.

Various other novel features, advantages and objects of my invention will be hereinafter more fully described and referred to in connection with the accompanying description, reference being had to the drawing wherein:

Fig. 1 is a front elevational view of the device of the invention;

Fig. 2 is a rear elevational view of the device of the invention; and

Fig. 3 is a sectional elevated view of the device taken along the line 33 in Fig. 2.

Referring to the drawing more in detail, the invention will now be fully described. Like numerals in different figures refer to like parts.

The device of the invention is generally contained within a frame or a casing. As shown, a casing is seen to have a front wall 10, side walls 12, a bottom wall 14 and a top wall 16. If it is desired, a rear wall 18 may also be provided.

A display panel 20 is disposed in an opening provided in the front wall 10 and the said panel consists of a main panel part having a frame member therearound. The panel 20 is stationary in its location in the front wall and is preferably more or less a part thereof as shown in Fig. 1. Its panel part contains a set or sets of light transmitting openings 22 therein.

Within the casing and extending parallel to and adjacent the panel 20 is a secondary display panel member 30. The latter also includes a panel portion 32 and a frame 34 is disposed therearound. The secondary panel portion likewise contains a set or sets of light transmitting openings 36.

The secondary panel 30 is movable relative to

the panel member 20 and the secondary panel is guided in its movements by guides 38. The guides 38 lead the secondary panel 30 upwardly and downwardly at a slightly inclined angle relative to the vertical axis of the device for reasons which will hereinafter more fully appear.

The secondary panel is held secure in its position between the guides and the first-named or adjacent panel 20 by suitable means such as buttons 39 or the like so that the secondary panel 10 is reciprocable therein.

A motor 40 is provided in geared relation with a cam 42 as by such usual means as a gear 44 and a shaft 46 which rotates the cam relative to the frame or casing.

A bar member 48 is associated with the secondary panel, substantially as shown in Fig. 3, and this overies the cam in such a way that the cam, when rotated, comes into engagement with the bar member and lifts the bar member 48. The latter being secured to the secondary panel, thus urges the secondary panel upwardly as it itself is moved upwardly.

It will thus be observed that the secondary panel is caused to slide relative to the stationary panel 20.

With further reference to the sets of light transmitting openings which are provided in each of the panels, the sets are so disposed that one of the sets on the panel 20 and the corresponding set on the secondary panel 30 are in register when the panels are in one certain relation and out of position when the panels are in another relative position. That is to say, when the secondary panel has reached its uppermost limit, one of the sets of light transmitting openings provided therein coincides with one of the sets of the openings in the panel 20. On the other hand, when the secondary panel 30 has reached its lowermost limit, another of the sets of light transmitting openings provided therein coincides with another of the sets of openings in the panel 20 so as to produce another and different effect.

The secondary panel is, as stated, preferably disposed at an angle relative to the other panel for the reason that certain of the openings in the two panels may be located in coinciding straight vertical lines and in such a case, the effect of suddenly appearing signs is lost.

It will be appreciated that the light transmitting openings in the panels may be arranged to present various designs and that there may be two or more panels if desired. While in the drawing I have shown the openings as presenting circular and rectangular devices, they may be
